US00D603503S

(12) **United States Design Patent**
Kriska et al.

(10) **Patent No.:** **US D603,503 S**
(45) **Date of Patent:** **** Nov. 3, 2009**

(54) **CERVICAL PLATE**

(75) Inventors: **Nickolas G. Kriska**, Canton, OH (US);
Richard N. Barros, II, Cuyahoga Falls,
OH (US); **Brian Edward Hockett**,
Parma, OH (US)

(73) Assignee: **Theken Spine, LLC**, Akron, OH (US)

(**) Term: **14 Years**

(21) Appl. No.: **29/320,796**

(22) Filed: **Jul. 3, 2008**

(51) **LOC (9) Cl.** **24-03**

(52) **U.S. Cl.** **D24/155**

(58) **Field of Classification Search** **D24/155-157;**
606/60, 61, 73, 95, 213, 281, 292, 70, 71,
606/76, 246, 248, 249, 247, 280, 283, 272;
623/17.11, 17.12, 17.13, 17.14, 17.15, 17.16,
623/23.61, 23.56, 247, 213, 286; **D15/143,**

CLAIM

The ornamental design for a cervical plate, as shown and described.

DESCRIPTION

FIG. 1 is a top perspective view of a cervical plate showing our new design;

FIG. 2 is a top plan view thereof;

FIG. 3 is a right side elevation thereof, the side opposite being a mirror image;

FIG. 4 is a rear elevation thereof, the end opposite being a mirror image; and,

FIG. 5 is a bottom plan view thereof.

1 Claim, 5 Drawing Sheets
